UNITED STATES PATENT OFFICE.

JESSIE B. FIELD, OF PORTLAND, OREGON.

COMBINATION-TABLE.

1,320,215.

Specification of Letters Patent.

Patented Oct. 28, 1919.

Application filed April 3, 1919. Serial No. 287,119.

To all whom it may concern:

Be it hereby known that I, JESSIE B. FIELD, a citizen of the United States, residing in the city of Portland, county of 5 Multnomah, and State of Oregon, have invented a new and useful Combination-Table, of which the following is a specification.

This invention relates more particularly 10 to that class of appliances known as tables as an article of furniture and having as its object the capacity of a multiple of tables, which may be used separately or jointly in any desired combination, while combining 15 utility and artistic effect in a high degree.

I attain these objects in the manner illustrated in the accompanying drawings and set forth in the specifications following.

Referring to the drawings. Figure 1 is 20 a plan of a semi-circular section which I have referred to as the receiving table; Fig. 2 is a front elevation of Fig. 1; Fig. 3 is a plan of two receiving tables joined together to form a card table; Fig. 4 is a 25 front elevation of a card table; Fig. 5 is a side elevation of a card table; Fig. 6 is a bottom view of a card table with the two halves locked together; Fig. 7 is a view similar to Fig. 6 but with the halves separated; Fig. 8 is an enlarged sectional view 30 along 8-8 in Fig. 6; Fig. 9 is a plan of library table of which Fig. 10 is a front elevation and Fig. 11 is a side elevation; Fig. 12 is an outlined plan of a breakfast 35 table; Fig. 13 is an outlined plan of a small dining room table; Fig. 14 is a plan of all of the tables joined together forming a large dining room table of which Fig. 15 is a cross section along the line 15-15 in 40 Fig. 14.

Similar letters and numbers of reference refer to the same or similar parts throughout the several views.

Referring in detail to the drawings. A¹ 45 is the top portion of receiving table of which A² is a supporting apron and A³ legs. On the under side of the top A¹ are fastened the slides A⁴ which are held in place by the guides A⁵. The slides A⁴ have their 50 ends A⁶ bent at a right angle to which is secured the movable apron A⁷. In the slotted member A⁸ is pivoted the eccentric lever A⁹ by means of the pin A¹⁰. To the center of the lever A⁹ is attached the rod 55 A¹¹ which has a bend near its center at A¹² and again at its extreme end A¹³. The rod

A¹¹ is arranged to slide in the bracket A¹⁴ and the bent end A¹³ is adapted to engage in an eye A¹⁵ on the bottom of the adjacent table top A¹. The lever A⁹ is operated by 60 means of the handle A¹⁶ and is held in a lateral position, which is slightly past its center, by the stop A¹⁷.

F¹ represents one half of the top of the library table of which F² forms a lateral 65 supporting apron and F³ is the end supporting apron while F⁴ represent the usual slides in a table of this type. The two halves of the library table may be latched together by the latches F⁵. Near the center 70 of each straight side F⁶ is placed an eye F⁷ which is similar to the eye A¹⁵ of the table top A¹. F⁸ are the legs for the table. F⁹ are extra leaves.

When it is desired to have the use of one 75 or two receiving tables it is only necessary to use the table shown in Figs. 1 and 2.

If it is desired to have a small card table both of the receiving tables are joined together as shown in Figs. 3, 4 and 5 and 80 held securely in place in every direction by means of the latch shown in Figs. 6 and 8. The operation of the latch can be best seen in Fig. 6 wherein the straight sides of the table top A¹ have been brought into their 85 proper relation and the movable slides A⁴ which carry the apron A⁷ are moved out so that the apron A⁷ on one table top will be in close contact with the similar apron on the second table top A¹. 90

To accomplish this it will be seen that it will be necessary for the apron A⁷ in moving as described to pass over the eye A¹⁵ on the adjacent table top A¹, thereby presenting the eye A¹⁵ to engagement with the 95 bent end A¹³ of the rod A¹²; it being observed in Fig. 8 that the bent end A¹³ does not drop down into the eye A¹⁵ until the central bend A¹² in the rod A¹¹ passes through the opening in the bracket A¹⁴, which permits the bent end A¹³ to descend into the eye A¹⁵. The required motion of the lever A⁹ will draw the pivot A¹⁰ to the end of the slot A¹⁸ in the part A⁸ and any further action of the lever A⁹ up to the moment it reaches the 105 stop A¹⁷ will increase the tension on the rod A¹¹ thereby securely drawing the two table tops A¹ firmly together.

The two receiving tables may be separated by merely reversing the operation of the 110 lever A⁹ and the shape of the central bend A¹² which passes through the hole in the

bracket A¹⁴ causes the bent end A¹³ to rise out of engagement with the eye A⁵ and permits the tables to be separated. A slight end pressure exerted on the bent end A¹³ causes the pivot A¹⁰ to slide in the slot A¹⁸ and permits the return of the movable apron A⁷ to its normal position underneath its own table top A¹.

When it is desired to use the table in the 10 shape shown in Fig. 13, which is that of a small dining room table, it is only necessary to bring the receiving tables into place at the end of the card table shown in Fig. 9 and engaging the bent end A¹³ of each of the 15 table tops A¹ with the eye F⁷ of the library table top F¹ and lock same in place in the same manner as described for joining the two receiving tables into a card table.

If it is desired to obtain a long dining 20 room table it is only necessary to release the latches F⁵ and slide the halves F¹ of the library top apart sufficiently to admit the desired number of extra table leaves F⁹.

It will be apparent to anyone that while 25 some of the individual features of the various tables I have illustrated have long been in use that the utility of being able to produce a great number of shapes and sizes of tables by the very simple operations described heretofore will not be questioned.

I claim:

1. In a combination table the combination of a plurality of tables adapted to be united in various forms, a concealed locking device 35 arranged to unite said tables in any desired arrangement, said locking device consisting of a hook mounted behind a slidable apron on the under side of a table in a manner that

when two tables are joined together said slidable apron may be moved outward to 40 a position underneath the adjoining table having moved past a catch in said adjoining table adapted to receive the hook of said locking device, an eccentric arranged to actuate said hook and lock same in the desired 45 position.

2. In a combination table, the combination of a plurality of separate units arranged to be rigidly joined together by means of a locking device consisting of a slidable apron 50 on the end of one table which is arranged to move outward between the side aprons of the adjoining table in a manner to expose the under parts of the adjacent sides of the table to the action of a locking means. 55

3. In a combination table, a concealed locking device consisting of a table top having fixed lateral aprons, a slidable end apron, a clamping hook secured to the under side of said table top and adapted to follow behind 60 said sliding apron, a catch mounted on the under side of the adjacent table top adapted to engage said hooks, said sliding apron being arranged to slide beyond said catch in a manner to expose the catch to the action 65 of said hook member, and a means for actuating and locking said hook consisting of an eccentric lever arranged to supply movement to said hook and lock same in position.

In testimony whereof, I have hereunto set 70 my hand in the presence of two subscribing witnesses.

JESSIE B. FIELD.
